UNITED STATES PATENT OFFICE.

RANSOM W. DAVENPORT, OF DETROIT, MICHIGAN, ASSIGNOR TO DETROIT STOVE WORKS, OF DETROIT, MICHIGAN, A CORPORATION OF MICHIGAN.

OVEN.

1,108,890.

Specification of Letters Patent. Patented Sept. 1, 1914.

Application filed November 25, 1912. Serial No. 733,518.

To all whom it may concern:

Be it known that I, RANSOM W. DAVENPORT, a citizen of the United States of America, residing at Detroit, in the county 5 of Wayne and State of Michigan, have invented certain new and useful Improvements in Ovens, of which the following is a specification, reference being had therein to the accompanying drawings.

10 The invention relates to ovens, being more particularly designed for use in connection with electric heaters.

It is the object of the invention; first, to obtain an effective heat insulation; further 15 to utilize the heat generated in one oven chamber either for heating the same or an adjacent oven chamber; and still further to obtain a convenient and effective arrangement of the heating elements.

20 With these objects in view, the invention consists in the construction as hereinafter set forth.

In the drawings: Fig. 1 is a perspective view of the oven, partly broken 25 away; Fig. 2 is a cross section; Fig. 3 is an enlarged section showing the arrangement of the heat-reflecting and non-conducting elements of the heat insulation; Fig. 4 is a view similar to Fig. 3 showing 30 a modified construction; Fig. 5 is a perspective view of the lamp and its fitting; and Fig. 6 is a cross section through one of the heating units.

A is the oven casing, which preferably 35 closes two superposed oven chambers B and C, the upper chamber constituting a baking oven, and the lower chamber a broiling oven.

40 D and D' are electrical heating units arranged respectively at the top of the chambers B and C, and in a position to radiate their heat downward.

E are doors at the front of the oven chambers B and C.

To make the most effective use of the heat 45 generated in the units D and D', the construction of the walls of the oven chamber is such as to form an effective heat insulation. This I preferably secure by combining alternate reflecting and non-conducting layers as 50 follows: F is an inner layer or lining of the oven, which is formed of some good heat-conducting material—such as sheet aluminum. Adjacent to this lining is a non-conducting layer formed in any suitable way, as

for instance, by a cellular body G which prevents circulation of the air. Beyond this non-conducting medium is another bright heat-reflecting surface I and then another non-conducting medium G' and another heat-reflecting surface I'. This alternation 55 of reflecting and non-conducting layers may continue to any extent desired, the outer case J being formed of any suitable material having the proper strength and rigidity. This construction insures partial reflection 60 of the incident radiating heat at the surface F, while that portion of the radiated heat absorbed by the reflector, together with the heat derived from the air in contact therewith, is prevented from rapid dissipation 65 by the adjacent non-conducting medium G. This non-conducting medium will cause a drop in temperature between its faces so 70 that the second heat-reflecting surface I will be at a lower temperature than the first surface F. With each succeeding alternate reflecting surface and heat-insulation there 75 will be a drop in temperature so that a very effective heat-insulation is obtained. Where, 80 the oven is used for ordinary cooking operations the temperature within the chamber will never rise to the point which will melt or destroy the aluminum sheets, and therefore this material, which has the property of retaining a bright surface even when heated 85 to a considerable extent, is best adapted for the inner lining; and the outer reflecting surface I, being always at a relatively low temperature, can be made of tin or other 90 bright metal which would be discolored if subjected to the inner-oven temperature. On the other hand where the oven is used for operations requiring a higher temperature which would be destructive to the 95 aluminum plates, as well as to all other available bright surfaces, I form the inner lining of iron K, or other suitable material, and place a non-conducting layer L immediately adjacent thereto, beyond which is the bright heat-reflecting surface F', as shown 100 in Fig. 4. The principle employed in both constructions shown in Figs. 3 and 4, is to place the heat reflecting surface as near the source of heat or inner lining of the oven chamber as is possible without destroying 105 said surface.

The heating units D and D' are preferably so constructed as to produce direct heat

radiation into the oven chamber from as large a portion of the resistor as possible. To secure this effect the heat resistor M is preferably in the form of a coil wound upon an electrical insulating core M', which extends horizontally adjacent to the top wall of the oven chamber, and this core is preferably substantially triangular in cross section, with the apex downward. By reason of this shape two-thirds of the resistor M will be arranged at angles permitting of direct downward radiation of the heat, while only one-third passes above the core and radiates heat upward. The heat radiating upward is reflected downward again by the bright lining F, but there is a loss due to the imperfection in the reflector, which is avoided in the portions of the resistor radiating directly downward.

20 In the lower oven chamber C, constituting the broiling oven, a reflector N, preferably of aluminum plate, is arranged above the heating unit D', to reflect downward any upward radiation from said heater. This reflector N does not, however, form a permanent portion of the partition between the ovens B and C, but said partition is formed by a plate O of dark metal—such as iron—which is a poor reflector and a good heat radiator. Thus whenever it is desired to use the heater D' for heating the bottom of the oven B, the reflector N is removed from its position between said heater and partition O, and is placed below the heater D', as indicated by the dotted line N' Fig. 2. This will reflect the downward radiation from the heater D' upward, and as the partition O is of metal having dark absorbing surface, being both a good heat radiator and heat conductor, the upwardly directed heat radiation will pass easily into the chamber B.

As electrical heating units are destructible it is desirable to mount the same so that they may be conveniently removed and replaced. 45 This I accomplish by forming in the side wall of the oven casing a channel P, in which the electrical conductors P' for connection with the heating units are placed, and which also contain insulator blocks Q, containing the terminal contacts. The heating units, including the core member M' and the resistor M wound thereon, are insertable through apertures Q' in the blocks Q, and the outer ends of said units are provided with terminal contacts R for engaging with the corresponding contacts on the blocks Q, thereby completing the connection of the unit with the electric circuit. The contacts R are preferably mounted upon a head member M² of the core member M', and are insertable in sockets Q² in the blocks Q, thereby effecting not only the electrical connection but also a mechanical coupling. The rods M² as well as the blocks Q, lie within the recess P, and when the parts are in posi-

tion a cover plate P² is secured to the oven casing to close the recess P. Thus at any time when the resistor of one of the units is burned out, it may be removed and replaced without skill or electrical knowledge on the part of the operator. A series of blocks Q is arranged in the channel P, and in addition to those which are employed as the heating units one or more of these blocks may be used for the connection of an electric light—such as S, Fig. 5—the bulb of which passes through this aperture Q' and illuminates the interior of the oven.

In operation, the electric circuits for the heating units are controlled by suitable switches, not shown, and may be used for heating either or both of the oven chambers B and C as desired.

What I claim as my invention is:

1. In an oven, a casing divided into a plurality of chambers, suitable heaters arranged therein, a heat reflecting shield adjustable to positions upon opposite sides of one of said heaters, a heat insulating wall, comprising a bright, metallic heat reflecting plate, positioned in said wall at the nearest point to the inner surface which is at a temperature below that which is destructive to the bright surface, and a heat non-conducting layer adjacent to the said heat reflecting plate. 85

2. In an oven, a casing divided into adjacent separate chambers, a heat insulating wall, comprising a bright metallic heat reflecting lining formed of material non-corrodible at the oven temperature, an adjacent layer of heat non-conducting material, an outer reflecting metallic plate of a material corrodible at the temperature of the wall in the position in which it is located, 105 and a plurality of recesses arranged in one of the walls of said oven and adapted to receive suitable heating units.

3. In an oven, a casing divided into a plurality of oven chambers, a heater in one of said chambers adjacent to the partition between the same and the other chamber, and means for directing the heat of said heater alternatively into the chamber in which it is located and into the adjacent chamber. 110

4. In an oven, the combination with a casing, divided into adjacent separated chambers, of an electrical heater in one of said chambers adjacent to the partition between the same and the other chamber, and an imperforate partition between said chambers, adjustable to vary the penetration of heat therethrough. 120

5. In an oven, the combination with a casing, divided into adjacent oven chambers, of an electrical heater in one of said chambers adjacent to the separating partition, an imperforate partition having a surface of good heat-absorbing and radiating material, and a heat-reflecting shield remov- 125

- ably placed between said heater and partition.
6. In an oven, the combination with a casting divided into adjacent oven chambers, of an imperforate partition between said chambers formed of a good heat-penetrating material, an electric heater in one of said chambers adjacent to said partition, and a heat-reflecting shield adjustable to positions upon opposite sides of said heater.
7. The combination with an oven having a recess in the wall thereof, of fixed electrical terminal contacts located in said recess, and an electrical heating unit insertible through an aperture in said recess into the oven casing; and having coöperating contacts for engaging with said fixed contacts.
8. The combination with an oven casing having a channeled wall, of electrical conductors located in the channel of said wall, a series of terminal contacts connected to said conductors and also located in said channel, a plurality of electrical heating units insertible through apertures in said channel into the oven chamber, contacts on said units for coöperating with the fixed
- contacts in said channel, and a removable cover for said channel.
9. In an oven, heaters arranged therein, a heat insulating wall, comprising a bright metallic heat reflecting lining formed of material non-corrodible at the oven temperature, an adjacent layer of heat non-conducting material, and an outer reflecting metallic plate of a material corrodible at the temperature of the wall in the position in which it is located.
10. In an oven, heating units arranged therein, a heat insulating wall, comprising a bright, metallic heat-reflecting plate, positioned in said wall at the nearest point to the inner surface which is at a temperature below that which is destructive to the bright surface, and a heat non-conducting layer adjacent to said heat-reflecting plate.

In testimony whereof I affix my signature in presence of two witnesses.

RANSOM W. DAVENPORT.
